W. F. Klemann

UNITED STATES PATENT OFFICE

CHARLES KLEEMANN, OF PALMYRA, AND EARL F. PATTON, OF BERLIN, NEW JERSEY

ELECTRIC-WIRE-CORD COILER

Application filed January 27, 1928. Serial No. 249,959.

The present invention relates to an improved electric wire cord or wire coiler, and the purpose of the invention is to provide a device of this kind which is simple, efficient and practical in construction and can be manufactured at relatively low cost and sold at a reasonably low profit.

Telephone or electric wire cords which are relatively pliable and yet have a certain amount of stiffness from one source of connection to another are sometimes bunched or fall in a mass, and not only become entangled with other objects, but also get entangled throughout their lengths, which is not only untidy but causes difficulty, when a lamp or telephone may be moved any great distance from its source of connection, or rather from its plug.

It is therefore another purpose of the invention to provide a coiler of this kind, which may be used for coiling the electric wire cord or wire, so as to provide a neat arrangement of the cord or wire, in order to avoid an untidy appearance and to prevent entanglement.

Still another purpose is to provide a coiler, consisting of a guide block to be held in one hand, together with a wire coiling rod mounted in the guide block, with means to attach the cord or wire to the rod, so that by rotating the rod (which has a crank handle), the wire cord may be coiled neatly to a small compass.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Fig. 1 is a view in perspective of the improved coiler constructed in accordance with the invention, showing the guide block in one hand and the crank handle grasped by the other hand, with a wire cord coiled upon the coiling rod; and Fig. 2 is a sectional view

through the guide block, showing the coiling rod in position.

Referring to the drawings, 1 identifies a guide block to be grasped in the left hand of the operator, and is provided with a longitudinal bore or hole 2, and engaging within the bore is a coiling rod 3. The guide block may be of any size and of any shape, while the bore or hole may be of any diameter.

The coiling rod may be of any length or any diameter, which would enable a wire cord to be coiled to any length; the convolutions of the coil therefore can be of any diameter.

One end of the coiling rod has a crank 4, which has a knob or handle 5. The knob or handle and the crank can be of any construction, and of any length.

Extending laterally of the coiling rod at a point adjacent the crank is an open hook-eye 6, with which a wire cord 7 may engage, the terminal plug 8 of which may assume a position adjacent the open hook-eye, to prevent the wire cord from being detached while the wire cord is being coiled upon the coiling rod.

In operation the wire cord may be connected to the open hook-eye, with the plug adjacent thereto, and then the crank may be rotated by grasping the handle 5, and as the coiling rod revolves it may be moved gradually out from the guide block, and the wire cord will therefore coil upon the coiling rod and arrange itself in a coil which may be of any suitable length. In this manner the wire cord can be arranged in a very small compass allowing it to take up very little room and prevent it from being entangled with itself or with any other object.

As the wire cord is being coiled, the end of the guide block guides the wire cord upon the coiling rod, and it is possible to move the block toward the cord as it is being coiled, so as to arrange the convolutions tightly against each other.

The invention having been set forth, what is claimed is:

1. A portable hand-operated tool for coiling electric wire cords, comprising a guide block adapted to be grasped in one hand and

provided with a guide bore formed longitudinally therethrough, a rotatable element operable in the bore and having means to attach an electric wire cord, which may coil on the element between said means and one end of the guide block, said element having a crank at one end beyond the attaching means and adapted to be gripped in the other hand, whereby upon rotating the element the cord may be coiled on the latter.

2. A portable hand-operated tool for coiling electric wire cords, comprising a guide block adapted to be grasped in one hand and provided with a guide bore formed longitudinally therethrough, a rotatable element operable in the bore and having means to attach an electric wire cord, which may coil on the element between said means and one end of the guide block, said element having a crank at one end beyond the attaching means and adapted to be gripped in the other hand whereby upon rotating the element the cord may be coiled on the latter, said element being relatively loose in the bore, whereby upon imparting quick reciprocating movements of the guide block toward the crank and vice versa, the convolutions of the coil on the element may be hammered close together.

3. In a portable hand-operated tool for coiling electric wire cords, the combination with a guide block adapted to be grasped in one hand and provided with a guide bore formed longitudinally therethrough, of a rotatable element operable in the bore and having an open hook-eye carried by the element, by which an electric wire cord can be attached to the element, so that the cord can coil on the element between the block and the eye, one end of the element beyond the eye having a crank to be grasped in the other hand for rotating the element, the element being loosely mounted in the bore whereby reciprocating movements may be imparted on the block and the element, the block moving toward the crank and vice versa, so that the convolutions can be hammered close together between the eye and one end of the block.

In testimony whereof they affix their signatures.

CHARLES KLEMANN.
EARL F. PATTON.
